US00D956041S

(12) **United States Design Patent** (10) Patent No.: **US D956,041 S**
Min et al. (45) Date of Patent: ** Jun. 28, 2022

(54) **MOBILE PHONE**

- (71) Applicant: **LG ELECTRONICS INC.**, Seoul (KR)
- (72) Inventors: **Jinki Min**, Seoul (KR); **Hongkyu Park**, Seoul (KR); **Jonhak Lee**, Seoul (KR); **Seunghyun Ji**, Seoul (KR); **Sojin Kim**, Seoul (KR)
- (73) Assignee: **LG ELECTRONICS INC.**, Seoul (KR)
- (**) Term: **15 Years**
- (21) Appl. No.: **29/729,063**
- (22) Filed: **Mar. 24, 2020**

(30) **Foreign Application Priority Data**

- Sep. 25, 2019 (JP) 2019-021445
- (51) LOC (13) Cl. **14-03**

(57) **CLAIM**

The ornamental design for a mobile phone, as shown and described.

DESCRIPTION

FIG. 1 is a front perspective view of the mobile phone showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a back perspective view thereof;

FIG. 9 is another front perspective view thereof, showing the mobile phone of FIG. 1 in an alternate configuration;

FIG. 10 is a front view of FIG. 9;

FIG. 11 is a rear view of FIG. 9;

FIG. 12 is a left side view of FIG. 9;

FIG. 13 is a right side view of FIG. 9;

FIG. 14 is a top plan view of FIG. 9;

FIG. 15 is a bottom plan view of FIG. 9; and,

FIG. 16 is a back perspective view of FIG. 9.

The broken lines depict portions of the mobile phone that form no part of the claimed design. The dash-dot broken lines define the bounds of the claimed design and form no part thereof.

1 Claim, 16 Drawing Sheets
